(Cl. D44—29.1)

To all whom it may concern:

Be it known that we, James T. Runkle and Philip F. Gassien, citizens of the United States of America, residing at Phoenix, in the county of Maricopa and State of Arizona, have invented a new, original, and ornamental Design for a Combination Tool, of which the following is a specification, reference being had to the accompanying drawing, forming part thereof.

Figure 1 is a top perspective of a combination tool, showing our new design; and

Figure 2 is a side elevational view thereof.

We claim:

The ornamental design for a combination tool, as shown.

JAMES T. RUNKLE.
PHILIP F. GASSIEN.
